UNITED STATES PATENT OFFICE.

WARREN F. FRASER, OF BOSTON, MASSACHUSETTS, ASSIGNOR TO WARREN F. FRASER CO., OF BOSTON, MASSACHUSETTS, A CORPORATION OF MASSACHUSETTS.

GRINDER.

1,267,534.

Specification of Letters Patent. Patented May 28, 1918.

Application filed March 29, 1917. Serial No. 158,415.

To all whom it may concern:

Be it known that I, WARREN F. FRASER, a subject of King George V of England, residing at Boston, in the county of Suffolk and State of Massachusetts, have invented new and useful Improvements in Grinders, of which the following is a specification.

This invention relates to an improvement in grinders and particularly to the mechanism whereby the direction of movement of the carriage is reversed. In mechanism of this character it is desirable and, in fact, necessary to stop the motion of the carriage accurately and quickly at a certain point when the direction of motion of the carriage is reversed. In order to secure this result the reversing mechanism must be operated very quickly and with great accuracy. This necessitates a spring-actuated mechanism and it is, therefore, essential that the reversing mechanism which is actuated by the spring or springs should be light as well as accurate, in order that said actuating spring or springs may perform the work quickly.

The object of this invention is particularly, therefore, to provide an easily operated and accurately working reversing mechanism.

It is further the object of the invention to provide such a mechanism which can be detached as a unit from the main portion of the machine, and which is so arranged that it can be easily inspected and adjusted.

To these ends the invention consists in the combination and arrangement of parts set forth in the following specification and particularly pointed out in the claims thereof.

Referring to the drawings:

Figure 1 is a front elevation of a grinding machine embodying my invention.

Fig. 2 is an enlarged elevation, partly broken away and shown in section, illustrating the reversing mechanism and the gearing forming a portion thereof.

Fig. 3 is a sectional elevation taken on line 3-3 of Fig. 1, the same being broken away.

Fig. 4 is a detail rear elevation, partly in section, as viewed from the rear of the machine or to the left of Fig. 3, illustrating the bevel gear reversing mechanism.

Fig. 5 is an enlarged sectional elevation of the lower portion of the reversing lever.

Fig. 6 is a detail front elevation of the bell crank lever stops and the rock-shaft arm 55 in connection with which they operate.

Like numerals refer to like parts throughout the several views of the drawings.

In the drawings, 10 is the main frame of the machine, 11 is the carriage, 12 is the head stock and 13 the tail stock. 14 is the carriage for the grinding wheel 15, the same being provided with a cross feed well known to those skilled in this art and forming no part of this invention. Rotary motion is imparted to the spindle of the head stock 12 by a pulley 16 and belt 17. A hand wheel 18 imparts a motion to the carriage 14 to feed the same crosswise of the carriage 11. The carriage 11 has a reciprocatory motion 70 imparted thereto by the following mechanism:

The main driving shaft 19 (Figs. 3 and 4) is rotated by any suitable means, such, for example, as a cone pulley (not shown in the drawings). Said main driving shaft has loosely mounted thereon a pair of bevel gears 20, 21, said bevel gears being rotatably mounted in bearings 22 on an auxiliary frame 23, said auxiliary frame also embodying studs 24 and a front plate 25 which is fastened by screws 26 to the main frame 10 and is detachable from said main frame as a unit, together with the reversing mechanism hereinafter described which is mounted 85 on said auxiliary frame.

Between the bevel gears 20 and 21 a clutch member 27 is slidably mounted upon the main driving shaft 19. The opposite ends of said sliding clutch member are provided 90 with teeth 28 and 29 adapted to engage corresponding teeth upon the gears 20 and 21, respectively. Said clutch member 27 is provided with an annular groove 30 in which are located blocks 31 which are connected to 95 an arm 32 fastened to a rock-shaft 33 which has bearings 34 and 35 in the auxiliary frame 23.

Said rock-shaft has a second arm 36 fastened thereto and extending downwardly 100 therefrom, the lower end of said arm 36 having a stud 37 fast thereto and forming, in effect, a portion thereof. Said stud 37 has a rectangular portion 38 midway of its length and its outer end terminates in a 105 cylindrical portion 39.

A lever 40 is pivotally mounted upon the sleeve bearing 35 which is fastened to the front plate 25 of the auxiliary frame 23 and said frame is mounted to rock upon said sleeve 35 which forms a pivot therefor. The lever 40 is held upon the sleeve 35 by a screw 42 which has screw-threaded engagement with the sleeve 35. The upper end of said lever 40 is provided with a handle 43.

- 10 A stud 44 is slidably mounted in the lever 40 and is held in position in said lever by a spring-actuated pin 45 which engages an annular groove 46 provided in the periphery of the stud 44. The stud 44 forms, in effect, 15 a portion of the lever 40 and projects rearwardly therebeyond into alignment with a pair of tappets 47, each consisting of a screw 48 having screw-threaded engagement with a bracket 49 which is adjustably fastened to 20 the carriage 11 by a bolt 50.

The lever 40 may be locked to the front plate 25 by means of a spring-actuated stud 51 or said stud may be held out of engagement with said plate by means of a cross-pin 25 52 (Fig. 3). The lever 40 is provided with a hub 53 in which is slidably mounted a pair of oppositely disposed spring actuated contact members 54, 55. Each of these contact members has a collar 56 fast thereto adapted 30 to slide in a recess 57 provided in the hub 53 and a spring 58 bears at one end against said collar 56 and at the other end against an adjusting screw 59 having screw-threaded engagement with said hub, whereby the adjacent ends of said contact members 54 and 35 55 are brought into contact with the cylindrical portion 39 of the stud 37, as illustrated in Fig. 5.

In order that the reversing mechanism 40 may be moved quickly and at a certain instant in the operation of the grinder, a pair of movable stops 60 and 61 are provided. These stops consist of bell crank levers, the 45 arms 62 of said levers being shorter than the arms 63. Said levers are mounted upon pins 64 which are fastened to the front plate 25 of the auxiliary frame 23. Said stops 60 and 61 are actuated by means of a spring 65 and stop pins 60' and 61' are provided to 50 limit the distance to which said stops may be moved by said spring. The outer ends of the arms 63 contact alternately with the opposite sides of the rectangular portion 38.

The hub 53 of the lever 40 has two studs 55 66 and 67 fast thereto and projecting laterally therefrom into alignment with the arms 62 of the stops 60 and 61, so that as the lever 40 is rocked upon its pivot alternately in opposite directions by the tappets 47 the pins 60 66 and 67 will contact alternately with the arms 62 of the stops 60 and 61 and will cause the reversing mechanism to be operated, as will be more fully hereinafter explained.

A reciprocating motion is imparted to the 65 carriage 11 by the bevel gears 20 and 21

which mesh into a bevel gear 68 which is fastened to a countershaft 69 rotatably mounted in a bearing 70 upon the auxiliary frame 23. A pinion 71 is fastened to the shaft 69 and meshes into a gear 72 which has 70 a pinion 73 fast thereto, said gear and pinion being rotatably mounted upon a stud 74 which is fastened to the auxiliary frame 23. The pinion 73 meshes into a gear 75 which is rotatably mounted upon a stud 76, also 75 fastened to the auxiliary frame 23, and said gear 75 meshes into a rack 77 fast to the under side of the carriage 11 (see Figs. 2 and 3).

When it is desired to operate the carriage 80 of the grinder by hand, it may be done by means of a hand wheel 78 which is connected to a shaft 79 having a pinion 80 fast thereto and meshing into the gear 75, and when the carriage 11 is moved by hand to adjust the 85 same to any desired position on the frame 10, the gearing whereby the carriage is automatically operated is disconnected from the driving shaft by means of a handle 81 (Fig. 1) which operates a clutch 82 (Fig. 3) to 90 disconnect the gear 72 from the pinion 73 in a manner well known to those skilled in this art, and thus the gear 75 will rotate the gear 73 which will rotate freely and independently of the gear 72 which leads, 95 through the train of gearing hereinbefore described, to the driving shaft.

When it is desired to have the machine operated automatically to impart a reciprocating motion to the carriage, the clutch 100 handle 81 is operated to throw the clutch 82 into operation and thus again lock the gear 72 to the pinion 73, whereby the driving train will be connected to the gear 75.

In order that access to the stops 60 and 61 105 and the parts adjacent thereto may be readily obtained, the hub 53 is provided with a plate 83 which is attached thereto by means of screws 84.

The general operation of the machine 110 hereinbefore specifically described is as follows: Assuming the parts to be in the relative positions illustrated in Figs. 1 and 2 and the carriage 11 moving in the direction of the arrow α , the screw 48 on the right 115 hand tappet 47 will eventually come into contact with the stud 44 forming a part of the lever 40 and will rock said lever upon its pivotal sleeve 35. This will cause the contact member 54, which rests at its right 120 hand end against the cylindrical portion 39 of the stud 37, to be pushed into the recess 57 and thus to compress its spring 58, while the contact member 55 will travel away 125 from said pin, and during this operation the outer end of the arm 63 of the stop 61 rests against the right hand end (Fig. 6) of the rectangular portion 38 of the stud 37. This stop 61, therefore, holds the arm 36 stationary during this portion of the op- 130

eration until the pin 67 on said lever 40 contacts with the arm 62 of the stop 61, and it will be noted that said pin 67 will contact with said arm at a point much nearer the 5 pivotal center of the stop 61 than is the outer end of the arm 63 where it bears against said rectangular portion 38, so that said outer end of the arm 63 will move a greater distance, substantially two to one, 10 as a matter of fact, than the pin 67 during a given time. This will, therefore, quickly trip the stop 61 and the spring 58 of the contact member 54 having been compressed by the motion of the lever 40 hereinbefore 15 described, the arm 36 will be rocked toward the right (Figs. 5 and 6) by the expansion of said spring and by the contact member 54 until the outer end of the arm 63 of the stop 60 slips in behind the left 20 hand side of the rectangular portion 38 of the stud 37 and stops against the stop pin 60', at the same time locking the arm 36 in its new position. The stop 60 will be moved, as hereinbefore described, by the spring 65 25 and the outer end of the arm 63 of the stop 61 will now bear against the under side of the rectangular portion 38 in a position similar to that formerly occupied by the stop 60 in Fig. 6.

30 The rocking motion imparted to the arm 36 will be transmitted by said arm to the rock-shaft 33 and to the rocker arm 32, thus causing the clutch member 27 to be moved out of contact with the teeth on the 35 hub of the bevel gear 21 and into engagement with the teeth on the hub of the bevel gear 20, so that the bevel gear 21 will run loose upon the shaft while the bevel gear 20 will become fast thereto and will drive the 40 bevel gear 68 in the opposite direction to that in which it formerly rotated, thus reversing the motion of the train of gearing embodying the pinion 71, gear 72, pinion 73 and gear 75 and, through the rack 77, reversing 45 the direction of motion of the carriage 11. Thus in time the tappet at the left of the lever 40 (Fig. 1) will engage the pin 44 and operate said lever in the opposite direction to that hereinbefore described and will again actuate the reversing mechanism, bringing the parts back to the 50 positions illustrated in the drawings.

It will be evident that if it is desired to get at the stops 60 and 61 or any of the 55 parts adjacent thereto, this can be readily done by removing the plate 83, and if it is desired to repair, adjust or in any way operate upon any of the different parts of the reversing mechanism hereinbefore described, 60 such work can easily be accomplished by removing the screws 26 from the plate 25, and the auxiliary frame, together with all the parts mounted thereon, can be readily slipped forward through the aperture 85 in the 65 frame 10.

Having thus described my invention, what I claim and desire by Letters Patent to seal and secure is:

1. A grinder having, in combination, a reciprocatory carriage, tappets on said carriage, a main driving shaft, gearing connecting said main driving shaft to said carriage and mechanism adapted to reverse the direction of rotation of said gearing and the direction of motion of said carriage comprising a rock-shaft, an arm thereon, a lever adapted to be alternately engaged by said tappets and thereby rocked alternately in opposite directions, a pair of oppositely disposed spring-actuated contact members mounted on said lever and engaging said arm on opposite sides thereof, a pair of oppositely disposed movable stops adapted to alternately engage said arm to lock the same against movement in one direction and a stationary support for said stops, said lever being adapted to alternately engage said stops and move them to allow said arm to be moved by one of said spring-actuated members, whereby said rock-shaft may be rocked alternately in opposite directions.

2. A grinder having, in combination, a reciprocatory carriage, tappets on said carriage, a main driving shaft, gearing connecting said main driving shaft to said carriage and mechanism adapted to reverse the direction of rotation of said gearing and the direction of motion of said carriage comprising a rock-shaft, an arm thereon, a lever adapted to be alternately engaged by said tappets and thereby rocked alternately in opposite directions, a pair of oppositely disposed spring-actuated contact members mounted on said lever and engaging said arm on opposite sides thereof, a pair of oppositely disposed spring-actuated bell crank levers adapted to alternately engage said arm to lock the same against movement in one direction, a stationary support for said bell crank levers and means on said lever adapted to alternately engage said bell crank levers and move them to allow said arm to be moved by one of said spring-actuated contact members, whereby said rock-shaft may be rocked alternately in opposite directions.

3. A grinder having, in combination, a reciprocatory carriage, a main frame upon which said carriage is arranged to slide, tappets on said carriage, a main driving shaft, gearing connecting said main driving shaft to said carriage and mechanism adapted to reverse the direction of rotation of said gearing and the direction of motion of said carriage comprising a rock-shaft, an arm thereon, a lever adapted to be alternately engaged by said tappets and thereby rocked alternately in opposite directions, a pair of oppositely disposed spring-actuated

- contact members mounted on said lever and engaging said arm on opposite sides thereof, a pair of oppositely disposed movable stops adapted to alternately engage said arm to lock the same against movement in one direction, a stationary support for said stops, said lever being adapted to alternately engage said stops and move them to allow said arm to be moved by one of said spring-actuated members, whereby said rock-shaft may be rocked alternately in opposite directions, and an auxiliary frame fast to said main frame upon which said gearing and reversing mechanism are mounted.
5. A grinder having, in combination, a reciprocating carriage, tappets on said carriage, a main driving shaft, a countershaft, a bevel gear fast to said countershaft, a pair of bevel gears mounted on said main driving shaft and meshing into said countershaft bevel gear, a clutch slidable on said main driving shaft and adapted to alternately lock each gear of said pair of bevel gears to said main driving shaft, gears connecting said countershaft to said carriage, a rock-shaft, an arm on said rock-shaft engaging said clutch, whereby the same may be moved longitudinally of said main driving shaft and alternately lock each gear of said pair of bevel gears to said main driving shaft, a second arm on said rock-shaft, a lever adapted to be alternately engaged by said tappets and thereby rocked alternately in opposite directions, a pair of oppositely disposed spring-actuated contact members mounted on said lever and engaging said second arm on opposite sides thereof, a pair of oppositely disposed movable stops adapted to alternately engage said second arm to lock the same against movement in one direction, a stationary support for said stops and means on said lever adapted to alternately engage said stops and move them to allow said second arm to be moved by one of said spring-actuated members, whereby said rock-shaft may be rocked alternately in opposite directions to shift said clutch and thereby cause said carriage to be moved in opposite directions.
4. A grinder having, in combination, a reciprocating carriage, a main frame upon which said carriage is arranged to slide, tappets on said carriage, a main driving shaft, gearing connecting said main driving shaft to said carriage and mechanism adapted to reverse the direction of rotation of said gearing and the direction of motion of said carriage comprising a rock-shaft, an arm thereon, a lever adapted to be alternately engaged by said tappets and thereby rocked alternately in opposite directions, a pair of oppositely disposed spring-actuated contact members mounted on said lever and engaging said arm on opposite sides thereof, a pair of oppositely disposed movable stops adapted to alternately engage said arm to lock the same against movement in one direction, a stationary support for said stops, said lever being adapted to alternately engage said stops and move them to allow said arm to be moved by one of said spring-actuated members, whereby said rock-shaft may be rocked alternately in opposite directions, an auxiliary frame fast to said main frame upon which said gearing and reversing mechanism are mounted, and means to lock said lever to said auxiliary frame.
